(57) **CLAIM**

The ornamental design for a electrical connector as shown and described.

DESCRIPTION

FIG. 1 is a front, bottom and left-side perspective view of an electrical connector showing my new design; FIG. 2 is a front, top and left-side perspective view thereof; FIG. 3 is a front elevational view thereof; FIG. 4 is a rear elevational view thereof; FIG. 5 is a left-side elevational view thereof; FIG. 6 is a right-side elevational view thereof; FIG. 7 is a top plan view thereof; FIG. 8 is a bottom plan view thereof; FIG. 9 is an enlarged view of the area 9 indicated in FIG. 1; and, FIG. 10 is an enlarged view of the area 10 indicated in FIG. 2.

The evenly-spaced broken lines are provided to show portions of the electrical connector that are not being claimed, and thus form no part of the claimed design. The single dot-dash broken lines define the boundary of the claimed design and form no part of the claimed design. The double dot-dash broken lines illustrated the boundary of an enlarged area of the design. The double dot-dash broken lines form no part of the claimed design.
